ROOFING

William Wallace Candler, Detroit, Mich.

Application July 12, 1934, Serial No. 734,750

1 Claim. (Cl. 108—7)

This invention relates to roofing and more especially to roofing materials, such as paper, felt, or the like, and to a method of preparing such roofing material so as to avoid trapping of air or gas between layers of the roofing sheets or between such sheets and the supporting surface therefor during application of the sheets.

It is common practice in the roofing art to use layers of a water-proofing paper, or felt, usually referred to as tarred or asphalt paper or felt, 10 suitably bonded to each other and to a supporting surface by an adhesive or cementitious composition. Usually several layers of this material are employed one over the other in lapped fashion 15 to constitute the roofing proper or to serve as a base for other roofing elements or coatings. The roofing paper or felt is usually composed of fibrous materials such as new or old rag fibers, wood or other vegetable fibers, asbestos, and the 20 like, with the fibers bonded together with an impregnating material, such as tar, oil, pitch, asphalt and the like, so that it is substantially impervious to air or gas as well as water.

In laying this type of roof, it is not at all 25 uncommon for blisters or pockets to form between the layers of felt or paper, or between these and the supporting surface therefor. This difficulty has been so prevalent and serious that there is an increasing tendency for roofers to use some other 30 and more expensive type of roof. This one difficulty has caused owners, roofers and manufacturers to be placed under enormous expense.

The principal object of this invention is to improve the art of roof construction.

35 A further object is to avoid the formation of pockets or blisters in the construction of a roof covering.

Another object is to provide an improved roofing felt or paper.

40 Another object is to provide a roofing paper or felt which is permeable to air or other gases without appreciably reducing the strength of this material.

A still further object is to provide an improved 45 method of preparing sheets of roofing material.

Other objects, features and advantages will become apparent from the following description and appended claim.

For the purpose of illustrating the application 50 of the invention and the method employed in fabricating the roofing material, reference may be had to the accompanying drawing, in which:

Figure 1 is a fragmentary perspective of a portion of a roof upon which sheet roofing material, prepared according to this invention, is employed;

Fig. 2 is a diagrammatic view of apparatus used in fabricating the roofing paper or felt;

Fig. 3 is a plan of the prepared felt or paper; and

Fig. 4 is an enlarged section taken substantially on the line 4—4 of Fig. 3.

In Fig. 1, a plurality of rolls 10 of roofing felt or paper 11 are shown in the process of constructing a roof covering. The rolls 10 are arranged so that as they are paid out or unwound, 10 the sheets 11 form a lapped or multi-ply covering with the plies secured together and to a supporting surface 12 by an adhesive or cementitious material 14, which may be in the form of hot tar, roofing pitch, asphalt, or cement, and the 15 like. In laying the roofing felt or paper, the adhesive material 14 is applied to the supporting surface 12 and to the portion of the plies which are to be covered by other plies then the rolls 10 unwind and the sheets 11 smoothed down by 20 means such as brooms, brushes, rollers, or the like.

To avoid the occurrence of pockets or blisters between the plies 11 of the roofing material or between the plies and the supporting surface 12, 25 the roofing felt is pierced as indicated at 15 in Figs. 1, 3 and 4, the felt being pierced at comparatively frequent intervals throughout its length and breadth to permit the passage of air or gas therethrough. Thus, as the rolls 10 are 30 unwound, any gas or air trapped below the sheets of roofing felt or paper is allowed to escape upwardly through the piercings 15 so that the felt may be readily and quickly smoothed against the supporting surface 12 and the plies of felt disposed therebelow. As the plies are smoothed down, the adhesive material 14 penetrates into the piercings 15 to close and seal the same, and at the same time extends through the piercings 35 so as to connect the adhesive material 14 on both 40 sides thereof and therefore effects a more intimate bond between the various plies and results in a more rigid and homogeneous assembly of the water proofing materials.

It is preferred to pierce the felt plies 11 with a 45 comparatively sharp needle-like means so as but slightly to separate or displace fibers thereof about the piercings 15 rather than to perforate the felt by cutting, punching or otherwise rupturing the fibers of the felt sheet. By piercing the sheet, 50 the fibers are not broken or to any great extent torn apart so that the strength of the prepared sheet is not appreciably reduced. By piercing, as distinguished from perforating, by cutting, tearing or otherwise rupturing the felt, small open- 55

ings only are left, which openings are readily closed and sealed by the adhesive material 14 so that each layer of felting, when applied, is rendered water-proof and closely adhered at all 5 points to the supporting surface or felting disposed therebelow.

Reference may now be had to Figs. 2, 3 and 4 which depicts the preferred method of fabricating the roofing felt, and the product effected 10 thereby. According to Fig. 2, the felt 11 is prepared by passing the same through a tank 20 containing, as previously indicated, a bonding or impregnating composition 21, such as tar, oil, asphalt, pitch, and the like, to impregnate the fibers 15 thereof and render the felt water-proof. The roofing felt or paper 11 may be fed from a reel 22 over guide rollers 23 and 25 and below a guide roller 24, and then wound on a reel 26 to provide a roll 10, such as is indicated in Fig. 1. Any desired or additional steps may be employed, such as removing surplus bonding or impregnating material, drying the sheets 11, applying talc or the like, or otherwise preventing layers of the rolls 10 from sticking to each other.

25 As the sheet material 11 is fed between the impregnating tank 20 and the winding reel 26, the piercings 15 are provided. These may be produced by a pair of rolls 30 and 31 driven in opposite directions by any suitable means (not shown) 30 at uniform peripheral speeds. Each of these rollers is provided with uniformly spaced needle-like projections 32 extending radially therefrom and arranged in substantially straight line rows in parallel, transverse, and diagonal directions with 35 respect to the axis of each roller. The rows or projections on each roller are spaced, for example, approximately 0.7 of an inch apart with the projections of each longitudinal or transverse rows spaced the same distance apart. The projections 40 of one roller, however, are staggered circumferentially and axially so as to space each piercing approximately 0.5 of an inch from the adjacent piercings, as indicated in Fig. 3. The rollers 30

and 31 are arranged in axially parallel position and preferably are spaced so that the projections 32 of each roller will pierce completely through the sheet material 11 as it is passed between the rollers.

5 As indicated in Figs. 3 and 4, the piercings of each longitudinal or transverse row are directed in the same direction and the piercings of alternate rows extending in opposite directions, while adjacent piercings of each diagonal row extend 10 in opposite directions. By forming the piercings 15 in this manner, the sheets 11 may be laid either sides down without closing, at the most, over half of the piercings so as to prevent the venting of air or gas therethrough. Half of the piercings 15 15 are produced by piercing from one face of the sheets and the other half by piercing from the opposite face thereof.

As illustrated in Fig. 4, the fibers 16 of the sheet material 11 are compressed or rendered 20 more compact adjacent the piercings 15 by the needle-like projections 32 of rollers 30 and 31 as the fibers 16 are separated or displaced. In this manner very few fibers are cut or torn away from other fibers so that the tensile strength of the 25 sheets 11 is not materially reduced.

As many changes could be made in the above 30 constructions and methods, and many apparently widely different embodiments and processes could be had without departing from the scope thereof, it is intended that all matter contained in the above description or shown in the accompanying drawing, shall be interpreted as illustrative and not in a limiting sense.

35 What is claimed is:

A roofing material comprising a sheet of felted fibrous material impregnated with and bonded together by an adhesive composition and being pierced at sufficiently frequent intervals subsequent to impregnation and in opposite directions 40 from each face thereof to vent gas freely therethrough in either direction.

WILLIAM WALLACE CANDLER.
